UNITED STATES PATENT OFFICE.

HOWARD EARL HOOVER, OF CHICAGO, ILLINOIS, ASSIGNOR TO THE HOOVER SUCTION SWEEPER COMPANY, OF NEW BERLIN, OHIO, A CORPORATION OF OHIO.

SUCTION-SWEEPER.

1,264,073.

Specification of Letters Patent. Patented Apr. 23, 1918.

Application filed September 9, 1916. Serial No. 119,168.

To all whom it may concern:

Be it known that I, HOWARD EARL HOOVER, a citizen of the United States residing at Chicago, in the county of Cook and State 5 of Illinois, have invented a certain new and useful Improvement in Suction-Sweepers, of which the following is a specification.

My invention relates to means for supporting the upper end of the bag on a suction sweeper so as to prevent the bag from dragging on the floor or getting under the wheels of the sweeper proper.

The particular object is to support such upper end of the bag in its proper position 10 to prevent dragging, regardless of the position of the handle and regardless of the condition of the bag, whether it be filled or not.

The invention consists in means for hanging the upper end of the bag so that it may automatically or by hand be moved along 15 the handle and retained normally at either end of its sliding excursion. The invention consists further in various details of construction set forth. It is illustrated in the accompanying drawings wherein—

Figure 1 is a side elevation of the suction sweeper containing one form of my invention with the handle inclined.

Fig. 2 is a side elevation of the same with the handle in an upright position.

Fig. 3 is a side elevation of the modified form of the suspended device.

Fig. 4 is a side elevation of the same form 35 with the handle in an upright position.

Fig. 5 is a detail of a modified form of the guide.

Like parts are indicated by the same letter in all the figures.

40 A is the sweeper proper to which is pivotally attached the handle B. C is a bag having at its lower end means whereby it is connected at C¹ with the dust discharge passage of the sweeper. D is a link attached to the center of the bag end at D¹.

D² is a hook which will seize the upper end of the link and is provided with the eye D³ slidable on the guide D⁴ on the handle B. This guide is parallel with but separated 45 from the handle. It is preferably provided with a loop D⁵ at its upper end. In the modified form of Figs. 3 and 4 the link takes the form of a ring D⁶ which is adapted to one edge of the bag end and directly 50 engages the hook.

This involves the use of a longer guide and therefore is not the preferred form. The loop in the guide may be dispensed with but when in this form there is no provision for holding the bag when it is in the position of Figs. 1 and 3 and deflated. 60

It will be understood, of course, that my drawing is to be taken as diagrammatic although it is a fairly faithful representation of the actual structure. I do not wish 65 to be limited to the particular form, shape, proportion and arrangement of parts here illustrated.

The parts D, D² and D³ together constitute the bag support which is slidably 70 mounted upon the guide.

The use and operation of my invention is as follows:

When the sweeper is out of use it preferably stands in the position of Figs. 2 or 4 75 and the ring or link together with the hook is at the lowest point of the excursion of the hook. The bag is properly supported in each case and it is not intended to drag on the floor. If, now, in either device, the 30 handle be thrown in the position of Figs. 1 or 3 the upper end of the bag can be moved by the hand until the hook falls into the loop. This action will result from inflating the bag in either form of the device 85 for as soon as the machine is in operation, the air passing into the bag from the sweeper tends to distend the bag and throws its upper end upwardly and outwardly along the handle until the hook drops into 90 the loop. In this position the bag is carried free from the ground whether it be empty or full, inflated or deflated and moved forwardly or backwardly. When the handle is tilted from the inclined to the upright 95 position the bag, whether full or empty, inflated or deflated, will slide the hook down along the guide the moment it is freed from the loop until the hook lies at the lower end of its excursion. 100

In the modified form of Figs. 3 and 4 no advantage is taken of the increased length of the bag owing to its deflation and it is necessary to have a longer guide.

In the case of a flat bottomed bag the 105 upper end of the guide or securing device is, under the normal conditions of operation, approximately in the plane of the bottom of the bag. The effect of this is that when the bag is inflated and the handle in this the 110

2
 normal position as illustrated in Fig. 1, the bottom of the bag forces the securing bag support up and along and finally to the upper end of the guide, where, if there be 5 a loop, it drops into the loop. This would not necessarily occur with a bag not having a flat bottom or with a guide not properly positioned. When the parts have thus been 10 operated and brought into the position in Fig. 1, the parts will remain in this position, and the machine can be moved around. The bag will not sink back into its unsupported condition the moment it is deflated. On the contrary, it will remain in the position indicated being held out of contact 15 with the floor.

I claim:

1. A bag holder for a suction sweeper having a handle, comprising a guide adapted to be secured on substantially parallel with, and slightly removed from the handle, a bag support adapted to be secured to the upper end of the bag and slidably mounted on the 20 guide.
2. A bag holder for a suction sweeper having a handle, comprising a guide adapted to be secured on substantially parallel with, and slightly removed from the handle, a bag support adapted to be secured to the upper 25 end of the bag and slidably mounted on the guide and means at the upper end of the guide to retain the slidable part at the upward end of its excursion.
3. A bag holder for a suction sweeper having a handle, comprising a guide adapted to be secured on substantially parallel with, and slightly removed from the handle, a bag support adapted to be secured to the upper 30 end of the bag and slidably mounted on the guide and a loop at the upper end of the guide to retain the slidable part at the upward end of its excursion.
4. A bag holder for a suction sweeper having a handle, comprising a guide adapted to be secured on substantially parallel with, and slightly removed from the handle, a bag 35

support adapted to be secured to the upper end of the bag and slidably mounted on the guide, said bag support containing an extension approximately equal to the radius of 50 the cross section of the bag and adapted to be secured approximately to the middle of the upper end of the bag in combination with a bag having a substantially flat upper end.

5. A bag holder for a suction sweeper having a handle, comprising a guide adapted to be secured on substantially parallel with, and slightly removed from the handle, a bag support adapted to be secured to the upper end of the bag and slidably mounted on the 60 guide and means at the upper end of the guide to retain the slidable part at the upward end of its excursion, said bag support containing an extension approximately equal to the radius of the cross section of the bag 65 and adapted to be secured approximately to the middle of the upper end of the bag in combination with a bag having a substantially flat upper end.

6. A bag holder for a suction sweeper having a handle, comprising a guide adapted to be secured on substantially parallel with, and slightly removed from the handle, a bag support adapted to be secured to the upper end of the bag and slidably mounted on the 75 guide and a loop at the upper end of the guide to retain the slidable part at the upward end of its excursion, said bag support containing an extension approximately equal to the radius of the cross section of the bag 80 and adapted to be secured approximately to the middle of the upper end of the bag in combination with a bag having a substantially flat upper end.

In testimony whereof, I affix my signature 85 in the presence of two witnesses this 1st day of Sept., 1916.

HOWARD EARL HOOVER.
